UNITED STATES PATENT OFFICE

2,406,182

BENDING APPARATUS

Arthur H. Zeitz, Kansas City, Mo., assignor of one-half to Charles S. Foreman, Kansas City, Mo.

Application September 11, 1943, Serial No. 501,965

6 Claims. (Cl. 153—32)

1

This invention relates to bending apparatus and more particularly to a bending machine for curving large pipes near their point of installation, and has for its principal object to bend pipe sections in a predetermined geometric curve.

In the construction of pipe lines, for example oil and gas pipe lines, it is necessary to bend the pipe sections to fit the contour of the ground where the line is laid. Due to the fact that it is difficult to handle and transport large pipe sections, particularly after they are curved, it is desirable that the sections be bent in the field near their point of use. The walls of such pipe are relatively thin and will therefore buckle easily requiring long gradual curves and extreme care in the bending operation.

It has been found that in bending large size steel pipe which have relatively thin side walls that all portions of the pipe must be bent simultaneously by a constant, slowly and evenly applied pressure to prevent buckling, also the more bucks used the less the chance of buckling the pipe.

Other objects of the present invention are therefore to provide a portable pipe bending machine; to provide a device adaptable for bending different diameters of pipes; to provide a bending machine with a plurality of simultaneously movable bending bucks; to provide for moving the bucks at a predetermined speed ratio for effecting a simultaneous even pressure throughout the length of the pipe being bent; to provide a machine with pivotally mounted bucks for changing the angle of contact between the bucks and pipe as said pipe is bent; to provide a central power device for applying power for moving the bucks to bend the pipe; to provide a plurality of inter-connected speed reducers for transmitting power to the respective bucks; to provide for moving each buck with an individual screw; to provide the screws for the respective bucks with threads having different leads for moving said bucks at different speed ratios; to provide the screws with threads the leads of which are related to provide relative speed ratios of the bucks to form the pipe in a predetermined curve; to provide an efficient, compact, and sturdy device for bending pipe; and to provide structural elements and arrangements thereof in a device of the character and for the purpose set forth.

In accomplishing these and other objects of the present invention, I have provided improved details of structure, the preferred form of which is illustrated in the accompanying drawings, wherein:

2

Fig. 1 is a plan view of a bending apparatus embodying my invention, portions of the top plate being broken away to better illustrate the drives for the respective buck operating screws.

Fig. 2 is a partial perspective view of the top of the machines, particularly illustrating one of the bending bucks.

Fig. 3 is a detail transverse sectional view on the line 3—3, Fig. 1.

Fig. 4 is a detail transverse sectional view on the line 4—4, Fig. 1.

Fig. 5 is a detail longitudinal sectional view on the line 5—5, Fig. 1.

Fig. 6 is an enlarged transverse sectional view through one of the bending buck guides.

Fig. 7 is a transverse sectional view on the line 7—7, Fig. 1, particularly illustrating the drive for the bending bucks.

Referring more in detail to the drawings wherein:

1 designates a pipe bending machine preferably supported on sills 2 and 3 extending longitudinally of the machine. The machine may be fixed on a permanent foundation, however, I prefer to make said machines portable by mounting the sills 2 and 3 on a frame 4 of a conventional trailer 5, the frame 4 being resiliently supported by springs 6 on axles 7 which are carried by wheels 8. The trailer may be of conventional structure and forms no part of the present invention other than serving to provide portability thereto.

Mounted on the sills 2 and 3, and preferably transversely thereof, are a plurality of spaced guide tracks 9, 10, 11, 12, 13, 14, 15, 16, and 17, said tracks preferably being spaced equally distant along said sills and preferably being of odd number whereby the central track 13 is located midway between the tracks 9 and 17 which are adjacent the ends of the sills. The tracks preferably consist of spaced channel members 18 and 19 having vertically arranged web portions 20 and upper and lower laterally extending flanges 21 and 22, the lower flanges 22 preferably being mounted on and secured to a plate 23 which is secured to the upper flange 24 of the sills 2 and 3. The flanges 21 and 22 extend inwardly of the tracks and their inner edges 25 are spaced to provide a slot 26 therebetween for a purpose later described. A plate 27 extends over the track members 9 to 17 inclusive, for forming a flooring or work surface 28, the plate 27 being carried by the flanges 21 of the channels forming the track members 9 to 17 and is secured thereto as by welding or the like. The plates 23 and

27 close the spaced flanges of the channels to form enclosed guides for retaining oil in which the parts therein may operate to provide lubrication therefor.

Mounted on one side of the machine is a box girder 29 extending above and below the track members 9 to 17 and having its outer face 31 secured to the track channel members 18 and 19, as at 32; the plate 30 is preferably braced by stiffeners or angles 33 which are rigidly secured to the outer faces of the channel web members as at 34. Mounted on the plate 30, are horizontally arranged I beams 35 and 36, flanges 37 adjacent the plate 30 being secured thereto by means of welding or the like as at 38 whereby the webs 38 and 40 of the respective I beams form the upper and lower walls of the box girder 29; the outer wall being formed by a plate 41 secured to the flanges 42 of the respective I beams. Not only does this structure form a housing but also rigidly connects the ends of the track members to form a rigid box girder. The other ends of the track members are connected by means of an I beam member 43 secured to the lower surface of the plate 23 adjacent the ends of the respective track members 9 and 17 inclusive, whereby the housing 29, the I beam member 43 and the sills 2 and 3 form longitudinal members through the apparatus which are each connected to the channels 18 and 19 of the respective track members 9 and 17 inclusive forming a rigid structure capable of withstanding hard usage and handling heavy pipe.

In the ends of each of the track members 9 and 17, adjacent the I beam 43, are thrust bearings 44 for rotatably supporting shafts 45 of screws 46 extending inwardly through the track members 9 and 17, the shafts 45 extending outwardly through apertures 47 in plates 48 which close the ends of the track members to enclose the bearings 44. The hand-wheels 49 and 50 are mounted on the outer ends of the shafts 45 in the tracks 9 and 17 respectively, said wheels being keyed to the shafts by means of splines 51 whereby operation of the hand-wheels rotates the screws in the respective track members. The hubs 52 of the hand-wheels 49 and 50 engage the outer face of the plate 48 to cooperate with collars 53 on the screws 46 having engagement with the inner portion of the bearings 44 to prevent lateral motion of the screws.

The screws 46 are threadedly engaged with nuts 54 slidably mounted between the channels 18 and 19 of the track members 9 and 17, whereby rotation of the hand-wheels 49 and 50 move the nuts 54 in said track members through engagement of the thread 55 on the screw 46 with internal threads 56 in the nuts 54. Pivots mounted on the respective nuts 54 are bucks 57 and 58 which preferably consist of foot plates 59 adapted to rest on the face 28 of the floor 27 and be connected to the nuts by means of cap-screws 60 extending through apertures 61 in the plates 59 and into threaded recesses 62 in the nuts 54. The screws 60 form bearing posts on which the bucks 57 and 58 may pivot as limited by engagement of the end of slots 63 in the plates 59, spaced toward the hand-wheels from the apertures 61 in the plates and shanks 64 of cap-screws 65, the shanks of which are threaded into threaded recesses 66 in the nuts 54. Mounted on the foot plates 59 adjacent the apertures 61 are upwardly extending plates 67 which are preferably secured, as by welding, in upright position on the plates 59 and braced by gusset plates

68, said gusset plates preferably being welded to the plates 59 and 67 and arranged on the side of the plates 67 toward the hand-wheels whereby the faces 69 of said plates 67 are toward the pipe 70 to be bent.

In order to adapt the bucks to the respective pipe size to be bent, pipe cradles 71 are mounted on the respective plates 59 in engagement with the plates 67. The cradles 71 preferably consist of laterally and vertically extending members 72 and 73 arranged at right angles, as at 74, and adapted to carry curved plates 75 which are of the same curvature as the pipe 70. The lower ends of the curved portions 75 are arranged horizontally, as at 76, and adapted to rest on the plates 72 and be secured therewith to the plates 59 by means of cap-screws 77, the upper ends of the curved plates 75 being connected, as at 78, with horizontal members 79 which are secured to the vertical plates 73, as at 80. The plates 73 are preferably secured to the plates 67 by means of cap-screws or the like 81 extending through apertures 82 in the plates 67 and threaded into threaded apertures 83 in the plates 73. With this arrangement the buck is pivotally mounted on the nuts 54 and slots 84 are provided in the plate 27 whereby turning of the hand-wheels 49 and 50 rotates the screws 46 to move the nuts 54 in the guide tracks 9 and 17 to adjust the position of the bucks 57 and 58 to engage the pipe 70 to be bent.

The intermediate tracks 19 and 16 inclusive are provided with thrust bearings 85 adjacent the box girder 29 for rotatably mounting shafts 86 of screws 87, 88, 89, 90, 91, 92, and 93 respectively. The shafts 86 extend through apertures 94 in the plate 30 for connection with gear reduction units 95 mounted on the plate 30 inside of the housing 29.

40 The gear reduction units 95 connected with the respective shafts 86 are preferably all of the same type and have worm drive shafts 96 extending laterally of said gear reduction units and longitudinally of the bending apparatus. Each of the 45 gear reduction units preferably have their shafts 96 connected by couplings 97 to the adjacent reduction unit whereby all of the gear reduction units are interconnected and are simultaneously operated by means of chain drives 98 and 99 having driving engagement with sprockets 100 and 101 arranged in spaced relation on the shafts 96 whereby the driving torque imparted to the shafts 96 is divided to reduce strain on the speed reducer shafts. Chains 98 and 99 are driven by means of sprockets 102 and 103 mounted on stub shafts 104, rotatably supported in bearings 105 on the plate 30. The stub shafts 104 also carry sprockets 106 and 107 which are operatively engaged by chains 108 and 109 which are driven by means of sprockets 110 on stub shafts 111 which is driven by means of chains 112 operating over sprockets 113 on a counter-shaft 114, said counter-shaft being driven by means of a belt or other suitable power transmission mechanism 115 from a prime mover, such as a gasoline engine 116, which is suspended by means of arms 117 preferably connected to the channel 3, as at 118, and the I beam 43, as at 119.

When the gasoline motor or other prime mover is operated, the worm shafts 96 are rotated through the transmission mechanism just described to transmit power through the respective gear reduction units to rotate the shafts 86 at a reduced speed. I prefer to provide each of the units 95 with the same gear reduction whereby

the screws 87 and 93 inclusive are rotated at the same speed as later described.

Each of the screws 87 and 93 inclusive is provided with collars 120 adapted to engage the thrust bearings 85 and cooperate with the gear reduction units to prevent endwise movement of the screws. Each of the screws extends in the respective tracks and the threads 121 thereon are threadedly engaged with internal threads 122 in the nuts 123 slidably mounted in the respective tracks. Pipe carriages or bucks 124 of exactly the same construction as the bucks 57 and 58 are pivotally mounted on the respective nuts 123 by means of cap-screws 125 extending through apertures in foot plates 126 in the respective bucks and threadedly engaged in threaded recesses in the respective nuts 123, the pivotal movements of the respective bucks being limited by means of cap-screws 127 extending through slots 128 in the plates 126 and threadedly engaged in threaded recesses 129, the plate 21 being slotted over the normal path of the screws 124 and 127 as at 130 to permit the nut and bucks to move transversely of the machine.

Secured to the carriages or bucks 124 are pipe cradles 131 substantially of the same structure as the cradles 71. The cradles 131 have curved faces 132 adapted to engage the side of the pipe to be bent, engagement of the cradles 131, moved by the respective screws 87 to 93 inclusive, being on the opposite side of the pipe to the cradles 71 which are adjustably moved by the screws 46.

I prefer to rotate each of the screws 87 to 93 inclusive at the same speed, and in the particular instance illustrated provide a variation in the leads of the threads on the respective screws whereby the ratio of the rotational speed of the individual screws to the linear speed of the respective bucks will increase as the screws are spaced from the center toward the ends of the machine. In the present instance I prefer that the screw 90 have a ratio of 3 threads to 1 inch, the screws 89 and 91 a ratio of 3.2 threads to 1 inch, the screws 88 and 92 a ratio of 4 threads to 1 inch, and the screws 87 and 93 a ratio of 6.85 threads to 1 inch. These are approximate figures and of course will vary with the spacing of the individual bucks. While I prefer to provide for the variation in linear travel of the individual bucks by using screws of different lead, it is believed obvious that a similar result could be obtained by changing the ratio of the gears in the respective gear reduction units.

In order to assist in placing a pipe 70 to be bent on the apparatus, I preferably provide extensions 133 on the sills 2 and 3 extending outwardly at each end of the apparatus and provide bearings 134 for rotatably supporting rollers 135 at the ends of the machine, the top of said rollers being substantially on the same level as the upper face 136 of the horizontal portion of the pipe engaging cradles 71 and 131.

The operation of a pipe bending apparatus constructed as described is as follows:

The pipe bending machine is moved in the field adjacent a point of use of the pipe and when pipe curves are needed to conform to the contour of the earth, the section of the pipe to be bent is placed on the apparatus, the ends thereof being supported by means of the rollers 135. The bucks 124 are all moved toward the housing 29 until the pipe engaging faces 132 of the respective bucks are in alignment. The pipe 70 is then arranged so one side thereof is engaged by the respective bucks 124 and the hand-

wheels 49 and 50 are rotated to move the bucks 57 and 58 into engagement with the opposite sides of said pipe. The prime mover 116 is then operated to transmit rotary motion to the counter-shaft 114 to drive the respective chains 112, stub-shafts 111, sprockets 106 and 107, stub-shafts 104, sprockets 102 and 103, chains 98 and 99, sprockets 100 and 101, to the worm drive shafts 96 of the respective gear reduction units 95, which simultaneously rotate the screws 87 and 93 at the same rotational speed. Due to the ratio of the leads of the respective screws 87 to 93, the bucks 124 are moved laterally of the apparatus to bend the portion of the pipe between the bucks 57 and 58, each of the bucks pivoting relative to the nuts 54 and 123 to maintain engagement of the pipe perpendicular to the tangent of the curve at the respective points of contact.

The curves placed in the pipes are measured by a scale 137 mounted on the plate 21 adjacent the buck 124 moved by the screw 90, said scale 137 preferably being graduated to indicate the degrees of the external angle formed by the tangents to the curve of the pipe. When the curvature is placed in the pipe the prime mover is reversed to reverse the screws 87 to 93 inclusive to withdraw the respective bucks from engagement with the pipe, and the hand-wheels 49 and 50 rotated to back the bucks 57 and 58 whereby the pipe may be picked up and removed from the apparatus. With this arrangement the bucks engage the pipe at relatively small spacing to exert an even force thereon and eliminate buckling of the pipe which is common in thin wall structures such as are used in cross-country pipe lines whereby a correct curvature may be imparted to the pipe without any obstructions or deformation thereof.

From the foregoing it is believed obvious that I have provided a pipe bending machine capable of bending pipe sections in predetermined geometric curves wherein pipes of different diameters may be efficiently and accurately bent to conform to the contour of the earth where the pipes are to be laid.

What I claim and desire to secure by Letters Patent is:

1. In a pipe bending machine, a frame adapted to receive a pipe to be bent, a plurality of guides arranged transversely of said frame, pipe engaging bucks movably mounted in the respective guides, the end bucks facing in the opposite direction of the intermediate bucks, means for adjusting the end bucks to effect engagement of all the bucks with the pipe, screws in the respective intermediate guides for moving the respective bucks, each of the screws located toward the center of the frame having longer lead than the adjacent outer screw whereby the center buck moves relatively faster than the outer bucks, and means for simultaneously rotating said screws in the intermediate guides for moving the respective bucks toward the pipe to bend said pipe.

2. In a pipe bending machine, a frame adapted to receive a pipe to be bent, a plurality of guides arranged transversely on said frame, pipe engaging bucks movably mounted in the respective guides, the end bucks facing in the opposite direction of the intermediate bucks, means for adjusting the end bucks to effect engagement of all the bucks with the pipe, screws in the respective intermediate guides for moving the respective bucks, each of the screws located toward the

center of the frame having longer lead than the adjacent outer screw whereby the center buck moves relatively faster than the outer bucks, a driving means, and speed reducers operatively connecting the driving means with the respective screws for simultaneously rotating said screws in the intermediate guides at the same rotational speed for moving the respective bucks toward the pipe at different speed ratios for bending said pipe in a curve.

3. In a pipe bending machine, a frame, a plurality of guides arranged transversely on said frame, followers mounted in the respective guides and movable transversely on the frame, carriages pivotally mounted on the followers, screws in the guides having engagement with the respective followers for moving same, said screws having different leads, pipe engaging bucks adjacent the ends of the frame for engaging one side of the pipe to be bent, pipe engaging bucks on the carriages and movable therewith for engaging the opposite side of the pipe intermediate of the first named bucks, and means for simultaneously rotating the screws in the respective guides for moving the followers and bucks thereon toward the pipe for bending said pipe, said carriages pivoting on the followers to maintain the force extended thereby at right angles to the pipe.

4. In a pipe bending machine, a frame adapted to receive a pipe to be bent, pipe engaging bucks mounted on the frame for movement transversely thereof, the end bucks facing in the opposite direction of the intermediate bucks, means for adjusting the end bucks to effect engagement of all the bucks with the pipe, screws in the frame and having engagement into the respective intermediate bucks for moving said bucks, each of the screws located toward the center of the frame having longer lead than the adjacent screw whereby the center buck moves relatively faster than the outer bucks, and means for moving the respective bucks toward the pipe to bend same in a curve.

5. In a pipe bending machine, a frame adapted

to receive a pipe to be bent, a plurality of spaced adjustable pipe engaging bucks mounted on the frame for movement transversely thereof, the end bucks adapted to engage one side of the pipe and the intermediate bucks the other side, means for adjusting the end bucks to effect engagement of all the bucks with the pipe before bending, means for moving said intermediate bucks toward the pipe, each of said moving means located toward the center of the frame moving the respective bucks faster than the next outer adjacent buck whereby the center buck moves relatively faster than the outer bucks, the moving speed of each intermediate buck being of predetermined ratio relative to the other bucks, and means for simultaneously operating said buck moving means for moving all of the intermediate bucks toward the pipe to bend same in a curve between the end bucks, said curve being determined by the relative speed ratios of the respective intermediate bucks.

6. In a pipe bending machine, a frame adapted to receive a pipe to be bent, a plurality of spaced adjustable pipe engaging bucks mounted on the frame for movement transversely thereof, the end bucks adapted to engage one side of the pipe and the intermediate bucks the other side, means for adjusting the end bucks to effect engagement of all the bucks with the pipe before bending, means for moving said intermediate bucks toward the pipe, each of said moving means located toward the center of the frame moving the respective bucks faster than the next outer adjacent buck whereby the center buck moves relatively faster than the outer bucks, a driving means, and speed reducers operatively connecting the driving means with the respective buck moving means for simultaneously operating said moving means to move the respective intermediate bucks toward the pipe to bend same in a curve between the end bucks, said curve being determined by the relative speed of the respective intermediate bucks.

ARTHUR H. ZEITZ.
